CLAIM

The ornamental design for a battery product for household portable power station as shown and described.

DESCRIPTION

FIG. 1 is a perspective view of a battery product for household portable power station showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 shown in FIG. 2; and, FIG. 10 is an enlarged view of portion 10 shown in FIG. 2. The dash-dash broken lines in the drawings depict portions of the battery product for household portable power station that form no part of the claimed design.

The dot-dash broken lines denote the boundaries of the enlarged portions of the article and form no part of the claimed design.

The oblique line shading in FIGS. 1 and 3 depicts the transparent and reflective surface of a part of the battery product for household portable power station.

1 Claim, 10 Drawing Sheets
